MINE CAR AND THE LIKE

Original Filed April 5, 1935 2 Sheets-Sheet 2

UNITED STATES PATENT OFFICE

2,097,967

MINE CAR AND THE LIKE

Glenn E. Edmunds, Columbus, Ohio, assignor to
The Bonney-Floyd Company, Columbus, Ohio,
a corporation of Ohio

Application April 5, 1935, Serial No. 14,941
Renewed August 30, 1937

5 Claims. (Cl. 105—364)

The present invention relates particularly to vehicles, such as mine cars, having independently sprung wheels of the type shown in my United States Patent No. 1,974,018, issued September 18, 1934, the present invention contemplating the use of the same type of independent wheel mounting yokes.

According to the aforementioned patent, the yokes are guided between side frames or sills, the outer of which must be demounted if the yokes are to be removed. Furthermore, according to the specific embodiment shown in the patent, the wheels can only be moved from the yokes by knocking out the stub axles.

According to the present invention, the yokes are demountable without disturbing the side frames or sills and the wheels may be dropped from the yokes without disturbing the wheel and axle assembly.

Furthermore, according to the present invention, I preferably provide snubber means, preferably in the form of springs, affecting the action of the main springs so that operation of the yokes is rendered smoother and sudden reactions of the main springs are prevented.

In the accompanying drawings, I have shown the invention in practical embodiment and description will be made with reference to this illustrative showing. In the drawings,

30 Figure 1 is a side elevation of a mine car embodying the present invention;

Figure 2 is a fragmentary view derived from Figure 1, on a larger scale;

Figure 3 is a section substantially on line 3—3 of Figure 2;

Figure 4 is a plan view of the showing of Figure 2, partly in section and with parts broken away or removed;

Figure 5 is a section substantially on line 5—5 of Figure 4;

Figure 6 is a section substantially on line 6—6 of Figure 4; and

Figure 7 is a fragmentary view showing a modified snubber arrangement.

45 Referring first to Figures 1 to 6, reference numeral 10 designates generally a mine car having a body which includes side walls as at 11, end walls, and a floor including a depressed central portion 12 running from end to end of the car and side portions or flare plates as at 13 running from end to end of the car. Main sills as at 14, preferably in the form of Z-bars, constitute risers between the central flooring and the flare plates as particularly shown in Figures 3 and 6, the lower inwardly turned flanges of the Z-bars being secured to

the lower inner marginal portions of the flare plates.

Angles as at 15 are secured to the upper marginal portions of the flare plates and to the lower inner marginal portions of the side wall. The ends of the main sills are joined by the end sill and bumper structures 16 and 17, the angles 15, which constitute auxiliary sills, being joined into the main sills by suitable means such, for example, as the body end walls.

Each flare plate is provided with a pair of longitudinally spaced wheel openings, one of the openings being indicated at 18a, Figure 3. Wheel housings as at 18 cover the wheel openings, each of the housings having a bottom horizontal perimetral flange overlying the margins of the wheel opening with which it is associated and riveted in position.

In Figure 1, two wheels 19 and 20 appear, the latter appearing also in Figures 2 to 6. A similar pair of wheels is disposed at the other side of the car as will be understood, but since the mounting of each wheel is in general the same, it will only be necessary to describe specifically the mounting shown in Figures 4 to 6.

An angle 21 has a horizontal flange riveted beneath the central portion of flare plate 13 and a vertical leg parallel to main sill 14. To the right hand end of angle 21 is secured a fitting generally designated at 22, the fitting having a tongue 23 riveted to the vertical leg of the angle. Fitting 22 includes a vertical wall portion 24 somewhat outwardly offset from the plane of the tongue 23.

At the ends of wall portion 24 vertical webs 25 and 26 project inwardly somewhat beyond the inner plane of angle 21, these webs being continued outwardly to provide gussets 25a and 26a whose upper edges are connected by a horizontal web 27 on which rests the flare plate 13. Web 27 is continued as at 27a inwardly of wall 24 up to the edge of the wheel opening 18a. Both the angle 15 and the wheel hood flange are riveted to the web 27, 27a through the flare plate so that an extremely rigid association of the parts is secured.

Fitting 22 beyond gusset 26a has a vertical wall portion 28 somewhat outwardly offset with respect to wall 24, the extremity of wall portion 28 being inwardly curved to form a guard 28a. Portions 28 and 28a are connected upwardly by a web 29 which is somewhat downwardly offset with respect to web 27a. On its lower face, web 29 is provided with a spring centering boss 29a.

To the main sill 14 is secured a bracket 30, the bracket having angular walls 31 and 32 of which the former is secured to the outer face of the

main sill, the latter projecting outwardly of the sill. The bracket has a top wall 33 provided on its underside with a spring centering boss 33a and with an eyeleted lug 33b.

5 Fitting 22 and bracket 30 are each preferably made as an integral steel casting.

A yoke generally designated at 34 has a tubular portion 35 of a length substantially equal to the distance between the main sill and the angle 10 or auxiliary sill 21 and is swivelled on a bolt 36 which is supported in perpendicular relation to the main sill in openings provided in the latter and in the vertical leg of angle 21. Parallel arms 15 37 and 38 project from tubular portion 35 and have at their free ends spring seats and spring centering bosses 37a and 38a which lie beneath bosses 33a and 29a, respectively. The upper edges of arms 37 and 38 are adjacent the lower face of the upper flange of the main sill and web 20 27a, respectively, and are adapted to abut the same to limit movement of the yoke and car understructure relative to each other. The yoke spring seats, as here shown, are on depressed end portions of the arms so as to provide adequate 25 space for compression springs 39 and 40 whose ends are engaged around the opposed centering bosses. The lower surfaces of webs or walls 29 and 33 are in the same plane so that springs 35 and 40 are interchangeable.

30 Just inwardly of boss 37a, arm 37 is outwardly expanded and provided with a downwardly open recess 41 rimmed at its upper portion by the parallel flanges 42 and 43 and the arched flange 44, these flanges being joined by a vertical web 45. 35 Arm 38 has a similar downwardly open recess 46 with a similarly outwardly offset formation 47, the vertical and arched flanges in this instance, however, being continued inwardly of the arm to provide a formation 48. A stub axle 49 is received 40 in the arm recesses and is held against downward displacement therein by means of pins 51 which bridge the recesses beneath the axle ends. Axial displacement of the axle is limited by the walls 45 as at 45 of the bearing formations, these walls 50 extending across the axle ends in proximity thereto. The bearing 48, Figures 3 and 4, projects between the vertical webs 25 and 36 of the fitting or casting 22, these webs extending downwardly below the normal position of the bearing formation and below the latter carrying a removable pin 52 for the purpose of limiting movement apart of the car understructure and yoke. The formation 48 is freely movable between webs 25 and 26 as particularly shown in Figure 4, the inner edges 55 of the webs serving as guide means for arm 38. The vertical web of main sill 14, in conjunction with wall portion 45, serves similarly as guide means for arm 37.

From the above, it will be seen that the wheeled 60 axle may be readily mounted in or removed from the yoke bearing when pins 50 and 51 are removed. Furthermore, upon removal of bolt 36 and pin 56, the yoke or yoke and wheel may be readily mounted in or removed from the yoke bearing when pins 50 and 51 are removed. Furthermore, upon removal of bolt 36 and pin 56, the yoke or yoke and wheel may be readily mounted or demounted without disturbing the car under-structure. The wheel and axle assembly may be 65 of any preferred design. I here show a cylindrical axle provided at its end with an integral annular shoulder 49a, Figure 3, against which abuts the retaining collar 53 of an antifriction bearing assembly, the other collar 54 being held in position by means of a nut 55 threaded on a portion 70 75

of the axle which is slightly enlarged, in order to take the threads, as regards the outer end portion 49b. Nut 55 is locked by a pin 56.

The free end of arm 37 is extended somewhat beyond the spring seat to provide an eyeleted lug 5 57 which lies beneath the eyeleted lug 33b, and the two lugs are connected by a tension spring 58, bracket wall 32 serving as a guard. Tension spring 58 acts as a snubber and gives the yoke 10 a smooth operation, eliminating violent reactions 10 of the main springs 39 and 40.

In the relation of parts herein shown, the car is assumed to be loaded. The design may be such that under all load conditions the car body will be yieldingly supported on the wheels. On the 15 other hand, when the car is fully loaded, the yokes may abut their upper stops. In any event, the main springs serve to keep the wheels on the track regardless of irregularities in height of the rails, the action of the main springs being modified by the snubbers. 20

In Figure 7, reference numeral 37' designates an arm similar to arm 37 above described except that in place of the lug 57, arm 37' has an extension 59 with spaced gussets as at 60 therebelow. 25 A bracket 30' is similar to bracket 30 but of smaller dimension since it provides no spring anchoring lug and its transverse wall 32' is shortened in order not to interfere with upward movement of lug 59 above which it lies. A bracket 61 30 secured to main sill 14 has an outwardly extending horizontal flange on which is secured one end of a leaf spring 62, the other end of the spring engaging under lug 59 between the gussets as at 60. Spring 62 has the same purpose as spring 35 58 previously described, the leaf spring, due to the friction between its leaves, having a superior action under some circumstances. Ordinarily, however, the spiral spring arrangement first described will be entirely adequate and preferable, 40 due to its simpler design. The snubber springs are of course of relatively small strength as compared to the suspension springs.

At its end opposite fitting 22, angle 21 has secured thereto a fitting 63 exactly the same as the 45 former except that it is reversely arranged, as will be understood. The associated yoke 64 is also reversely arranged as regards yoke 34. It will be understood that the wheel mounting arrangement is duplicated on the other side of 50 the car.

As here shown, the pivot bolts for the yokes are toward the center of the car. They could, of course, be toward the ends of the car or both could be toward the same end. It will be understood that other variations may be made from the illustrative constructions herein described without departure from the invention and that accordingly I do not limit myself except as in the following claims. 60

I claim:—

1. A car comprising an under-structure and wheels on which said under-structure is supported, mounting means for each wheel comprising a yoke extending in the longitudinal direction of 65 the car and in pivotal connection with the under-structure on an axis extending transversely of the car, a stub axle carried by each yoke remote from its pivotal axis and upon which a car wheel is mounted, spring means interposed between the 70 under-structure and each yoke remote from the pivotal axis of the same whereby the under-structure is yieldingly supported on the wheels, brackets secured to the under-structure at the free ends of the yokes and each having a portion 75

overlying the projecting portion of the adjacent yoke, and tension springs respectively connecting said projecting portions and said overlying portions of the brackets, said brackets including 5 transversely extending walls constituting guards for the springs.

2. A car comprising an under-structure and wheels on which said under-structure is supported, mounting means for each wheel comprising 10 a yoke extending in the longitudinal direction of the car and in pivotal connection with the under-structure on an axis extending transversely of the car, each of said yokes comprising a pair of arms extending side by side and provided with 15 downwardly open recesses remote from the pivoting axis of the yoke, each yoke having a stub axle received in its arm recesses and removable means bridging the recesses beneath the axle to hold the axle in the recesses, the wheels being 20 mounted on the axles between the respective yoke arms, means limiting axial displacement of the axles, spring means between said yokes and said under-structure whereby the latter is yieldingly supported on the wheels, and removable pins limiting movement apart of the under-frame and 25 yokes.

3. A car comprising an under-structure and wheels on which said under-structure is supported, mounting means for each wheel comprising a 30 yoke extending in the longitudinal direction of the car and in pivotal connection with the under-structure on an axis extending transversely of the car, each of said yokes comprising a pair of arms extending side by side and provided 35 with downwardly open recesses remote from the pivoting axis of the yoke, each yoke having a stub axle received in its arm recesses and removable means bridging the recesses beneath the axle to hold the axle in the recesses, the wheels being 40 mounted on the axles between the respective yoke arms, means limiting axial displacement of the axles, said last-named means being constituted by wall portions of the yoke arms extending across the ends of the axles, spring means

between said yokes and said under-structure whereby the latter is yieldingly supported on the wheels, and means limiting movement apart of the under-frame and yokes.

4. A car comprising an under-structure and 5 wheels on which said under-structure is supported, mounting means for each wheel comprising a yoke extending in the longitudinal direction 10 of the car and in pivotal connection with the under-structure on an axis extending transversely of the car, each of said yokes comprising a pair of arms extending side by side and provided with downwardly open recesses remote from the pivoting axis of the yoke, each yoke having a stub axle received in its arm recesses and removable 15 means bridging the recesses beneath the axle to hold the axle in the recesses, the wheels being mounted on the axles between the respective yoke arms, means limiting axial displacement of the axles, spring means between said 20 yokes and said under-structure whereby the latter is yieldingly supported on the wheels, an arm of each of said yokes having an outward protuberance and said under-structure having downwardly open recesses receiving said protuberances, 25 and removable means bridging said last named recesses below said protuberances to limit movement apart of the under-frame and yokes.

5. A wheel mounting yoke comprising a pair 30 of arms extending side by side and rigidly joined together at one end, pivoting provisions at said end whereby the yoke is pivotal about an axis perpendicular to the arms, the arms having open ended recesses extending transversely of a plane 35 which includes said axis and in which recesses the ends of a stub axle are insertable, the arms having integral portions at their outer sides connecting the edges of the recesses for the purpose of strengthening the arms and holding a stub axle against axial movement out of the recesses, 40 the recess walls having provisions for engagement by removable axle-retaining means.

GLENN E. EDMUND.
